2,503,110

TOBACCO SMOKE CONDITIONING DEVICE

William J. Heiland, Rutherford, N. J.

Application December 28, 1945, Serial No. 637,646

1 Claim. (Cl. 131—10)

1

This invention relates to a device for conditioning the smoke of tobacco in cigarettes, cigars and pipes.

It is an object of the invention to provide a simple and inexpensive form of tip which, when properly placed on a cigarette, cigar or pipe will act upon the smoke before it reaches the mouth of the user so that an agreeable odor can be imparted thereto or medicinal properties imparted to the smoke, or the smoke can be filtered.

Another object is to provide a device of this character which can be very cheaply made, can be packaged readily so that quantities can be nested for compactness and which can easily be applied to the object to be smoked.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawing the preferred form of the invention has been shown.

In said drawing

Figure 1 is a central longitudinal section through the article prior to the pressure of a cigarette thereinto, a cigarette being illustrated in one end portion of the device.

Figure 2 is a view similar to Figure 1 showing the relative positions of the parts after a cigarette has been forced into position within the tip.

Figure 3 is a section on line 3—3 Figure 2.

Figure 4 is a side elevation showing a number of the articles nested for packing and shipment.

Figure 5 is a detailed view of a blank from which the body of the device can be formed.

Figure 6 is a view of the blank from which the conditioning element can be made.

Figure 7 is a view of a blank from which a modified structure can be formed.

Referring to the drawing in detail, 1 designates a sheet of paper or any other suitable material which can be provided along one edge with adhesive as shown at 2, this strip 1 being so shaped that when it is rolled and the supposed edges joined, it will produce a tapered frustoconical body as indicated at 3 in Figures 1, 2 and 4. The proportions of the body thus formed are such that one end of a cigarette C can be wedged thereinto after being inserted a predetermined distance.

2

Located within the body 1 at a point between its ends is a strip of material 5 having long tapered fingers 6 extending from one edge thereof. This strip can be of any suitable material which will give the results desired. For example it can be of an absorbent paper for holding a perfume or a medicine which will produce a vapor, when heated.

In practice the strip 5 is rolled into cylindrical form so as to leave a cluster of the fingers 6 extending from one end thereof and the rolled strip is then inserted into the middle portion of the body 3 so that the fingers will be extended toward the large end of the body and will be 15 slightly spaced from the wall of the body.

When a cigarette C is to be used with the device, one end thereof is thrust into the large end of the body 3 and against the free ends of the fingers 6. This will cause the fingers to 20 crumple or fold inwardly toward each other so as to form a partition of overlapping portions as shown in Figures 2 and 3 and thereafter while the cigarette is being smoked, the generated smoke, before reaching the mouth of the user 25 must pass through this partition. Here it will be filtered or scented or medicated, according to the type insert used.

In shipping the articles they can be nested as shown in Figure 4 and they can thus be sold 30 in quantities to a customer who, as he uses them, need only withdraw them one at a time and apply them to the cigarette.

Obviously similar tips can be used with cigars and with the stems or the mouthpieces of tobacco pipes and in every case the same results 35 will be obtained.

Furthermore, if desired, the tip herein described can be sold as a permanent part of a cigarette or cigar in which case the crushing of 40 the filter will take place when the parts are combined prior to being placed on the market.

The tips can be of any desired proportion, depending upon the type of article with which 45 they are to be used.

It is to be understood, furthermore, that instead of inserting the filtering element into the finished tip, it can be affixed to the blank 1 before the said blank is shaped so that one operation of shaping the blank and the filter is all 50 that is required in producing the article. This arrangement has been disclosed in Figure 7 of the drawing wherein the main blank has been indicated at 7 and the filtering element thereon has been indicated at 8.

Although the fingers of the filtering element

have been shown and described as pointed, it is to be understood that they can be made of any other shapes desired.

A further improvement consists of a wad of medicated or otherwise treated fibrous material such as cotton, which can be placed on the filtering element 5 or 8, so as to be rolled thereby into when the article is shaped thereby to be surrounded and overlapped by the fingers and other portions of the filtering blank. This applied filtering wad has been indicated at 9.

Obviously various other modifications may be embodied in the device without departing from the spirit of the invention as claimed.

What is claimed is:

A device of the class described, including a hollow and gradually tapered body having its large end of slightly greater diameter than the diameter of a cigarette insertable therein, whereby said cigarette will be wedgingly engaged when inserted intermediate the ends of the body, a member within the body, and relatively elongated crushable fingers extending from one end of the member toward, but terminating short of,

the large end of the body, said fingers normally defining a substantially cylindrical extension of the member, whereby to be spaced at their free ends from the wall of the hollow body, and said fingers defining an obstruction in the path of the inserted cigarette, whereby to be wholly crumpled by the end of the cigarette when it is wedged into the hollow body.

WILLIAM J. HEILAND.
